ROTARY BRUSH TYPE APPARATUS FOR
WASHING ROOFS OF RAILWAY CARS
AND OTHER VEHICLESLouis D. Holmes, Blue Island, Ill., assignor to
Whiting Corporation, Harvey, Ill., a corpora-
tion of Illinois

Application March 2, 1949, Serial No. 79,272

12 Claims. (Cl. 15—53)

1

The present invention relates generally to apparatus for washing the roof portions of railway cars or like vehicles. More particularly the invention relates to that type of washing apparatus which operates to effect washing of the roof portions during propulsion of the railway cars therepast at a comparatively low rate of speed and as its principal components or parts comprise a vertically elongated supporting structure at one side of the runway or track for the cars, and a frame having an elongated rotary motor driven brush thereon, pivotally mounted with respect to the supporting structure to swing into and out of an operative position wherein the rotary brush engages the roof portion of the car being washed, and provided with pneumatic means for swinging it into its operative position and counterweight means for retracting it into its inoperative position when the pneumatic means is de-energized or rendered ineffective.

One object of the invention is to provide a washing apparatus of this type which is an improvement upon, and has certain inherent advantages over, previously designed apparatus for the same purpose and of the same general character and is characterized by high efficiency, simplicity of construction and a novel arrangement of parts.

Another object of the invention is to provide a washing apparatus of the type under consideration in which the supporting structure at one side of the runway or track for the cars to be washed comprises an elevated upstanding mast which is pivoted to rotate back and forth about a vertical axis, and a boom which is connected to the lower end of, and projects laterally from, the mast, has the brush carrying frame pivotally suspended therefrom, and is adapted in response to rotation of the mast to swing bodily back and forth between a working position wherein it extends transversely of, and over, the runway and a nonworking position wherein it is disposed at one side of, and in parallel relation with, the runway, and hence frees the runway so that railway cars may be propelled unimpeded therewith.

Another object of the invention is to provide a washing apparatus of the last mentioned character in which the mast has associated therewith simple and novel power actuated mechanism for rotating it back and forth in order to swing the boom between its working and nonworking positions.

Another object of the invention is to provide a washing apparatus of the type and character

under consideration in which the pneumatic means for swinging the brush carrying frame into and out of its operative position is in the form of an air cylinder which is mounted on the boom, is operatively connected to the frame by way of a pair of bell crank forming arms, a link and a third arm, and has associated therewith means for limiting its stroke to the end that the arc of swing of the frame resulting from actuation of the air cylinder is substantially constant.

A further object of the invention is to provide a washing apparatus of the last mentioned character in which the air cylinder constituting the pneumatic means for swinging the brush carrying frame into and out of its operative position is carried by a motor operated screw type unit which is capable of being operated so as bodily to move the air cylinder back and forth in order either to change the position of, or increase, the arc of swing of the brush carrying frame.

A still further object of the invention is to provide a washing apparatus which is generally of new and improved construction, effectively and efficiently fulfills its intended purpose and is capable of being produced and operated at a comparatively low cost.

Other objects of the invention and the various advantages and characteristics of the present apparatus for washing the roof portions of railway cars will be apparent from a consideration of the following detailed description.

The invention consists in the several novel features which are hereinafter set forth and are more particularly defined by claims at the conclusion hereof.

In the drawings which accompany and form a part of this specification or disclosure and in which like letters and numerals of reference denote corresponding parts throughout the several views:

Figure 1 is a rear elevation of a washing apparatus embodying the invention, the boom being shown in its working position wherein it extends over and transversely of the runway for the cars, the roof portions of which are to be washed;

Figure 2 is an outside side elevation of the apparatus;

Figure 3 is a rear elevation showing the boom constituting a part of the supporting structure after swinging thereof into nonworking position but before upward swinging of the motor driven brush;

Figure 4 is a plan view of the brush carrying frame while the frame is in a horizontal position;

Figure 5 is a side elevation of the frame;

Figure 6 is an inside side elevation of the power actuated mechanism for rotating the mast in order to swing the frame carrying boom back and forth between its working and nonworking positions;

Figure 7 is a rear elevation of the mechanism which is illustrated in Figure 6;

Figure 8 is a front elevation of the boom illustrating in detail the construction and manner of mounting of the air cylinder and the motor operated screw type device for bodily shifting the air cylinder back and forth, certain parts being broken away and other parts being shown in section for purposes of illustration;

Figure 9 is a vertical transverse section taken on the line 9—9 of Figure 8 and illustrating in detail the construction and arrangement of the motor and gearing constituting the operating means for the screw type device;

Figure 10 is a vertical transverse section taken on the line 10—10 of Figure 8; and

Figure 11 is a vertical transverse section taken on the line 11—11 of Figure 8 and showing the cross sectional construction of the boom and the design and arrangement of the arms and link that constitute the operating connection between the air cylinder and the brush carrying frame.

The apparatus which is shown in the drawings constitutes the preferred form or embodiment of the invention. It is designed and adapted automatically to wash the roof portion of a railway car C as the latter is propelled on a runway or track (not shown) past the apparatus and as its principal parts comprise a concrete pier 12, a supporting structure 13, a frame 14 and a brush 15.

The pier 12 is located at one side of the aforementioned runway along which the car C is propelled past the washing apparatus in connection with washing of the roof thereof, and is vertically elongated. The lower end of the pier is suitably anchored in place and the upper end terminates at approximately the elevation of the roof of the car C and is surmounted by a fixed horizontally extending bed plate 16. The purpose of the pier 12 is to support the supporting structure 13.

The supporting structure 13 serves as a mounting or carrying medium for the frame 14 and consists of a standard 17, a mast 18, a boom 19 and a brace 20. The standard 17 is mounted on, and forms an upper extension of, the pier 12 and is rectangular in cross section. The lower end of the standard rests directly on, and is suitably fixedly connected to, the front outer portion of the bed plate 16 on the upper end of the pier. The mast 18 extends truly vertically and is located directly rearwards of the standard 17. It is preferably in the form of a metallic tube of comparatively large diameter and wall thickness and has a fixedly mounted, downwardly extending pintle 21 at its lower end and a fixedly mounted upwardly extending pintle 22 at its upper end. The pintle 21 at the lower end of the mast is journaled in a bearing 23 on the bed plate 16 and the pintle 22 at the upper end of the mast is journaled in a bearing 24 which is fixedly connected to the upper end of the standard 17 and extends rearwards, i. e., in the direction in which the car C is propelled along the runway in connection with a roof washing operation. The two pintles 21 and 22 together with their bearings form a pivotal mount whereby the mast 18 that is directly rearwards of the standard 17 is permitted

to rotate or turn back and forth about a vertical axis. The boom 19 of the supporting structure 13 extends laterally from the lower end of the mast and is preferably in the form of a channel beam. It consists of a web and a pair of upwardly extending side flanges, as best shown in Figures 9, 10 and 11, and has its inner end pivotally connected to the lower end of the mast by way of a pair of bearing brackets 25 and a pair of trunnions 26. The bearing brackets are fixedly connected to, and project outwards of, the inner ends of the side flanges of the boom 19. The trunnions 26 are fixedly connected to, and project laterally in opposite directions from, the lower end of the mast 18 and extend through the bearing brackets 25. The bearing brackets and trunnions serve to connect the boom so that it swings laterally in response to rotation of the mast and is also capable of swinging upwards and downwards relatively to the mast. The brace 20 of the supporting structure extends between the upper end of the mast 18 and the outer end of the boom 19 and constitutes a tension type suspension member for the boom. As shown in Figure 1, the brace 20 supports the boom so that it extends upwards at an acute angle with respect to the horizontal. The upper end of the brace 20 is provided with a clevis 27 which surrounds the upper end of the mast 18 and is pivotally connected thereto by way of horizontal, oppositely extending trunnions 28. The lower end of the brace 20 is pivotally connected to the outer or distal end of the boom 19 by way of a horizontal pivot pin 29 which extends through the brace and has its ends mounted in holes in the outer ends of the side flanges of the boom 19. The clevis 27 is adjustably connected to the upper end of the brace in order that the operative length of the brace may be increased or decreased for purposes of adjusting or varying the angular position of the boom 13. When the clevis is adjusted toward the brace so as to shorten the operative length of the brace the angle of the boom with respect to the horizontal is increased. Adjustment of the clevis away from the brace increases the operative length of the brace and hence serves to decrease the angle or inclination of the boom. By adjusting the clevis either toward or away from the adjacent end of the brace the boom may be set at any desired angle. When the washing apparatus is in operation the boom 19 assumes a working position wherein, as shown in Figure 1, it overlies, and extends transversely of, the runway along which the railway car C is propelled. When the apparatus is not in use the boom, due to its mounting, is adapted to be swung rearwards into a nonworking position wherein it is disposed at one side of, and in parallel relation with, the runway, as shown in Figure 3 of the drawings.

For the purpose of swinging the boom 19 back and forth between its working and nonworking positions the washing apparatus is provided with power operated mechanism 30. The latter is illustrated in detail in Figures 6 and 7 of the drawings and comprises an air cylinder 31, an inverted T-shaped lever 32, a link 33, an arm 34, and a counterweight 35. As hereinafter described more in detail the air cylinder 31, when energized, operates to swing the boom 19 into its working position and to maintain the boom in such position, and the counterweight 35 operates, when the air cylinder is de-energized or rendered ineffective, to swing the boom into its nonworking position wherein, as previously pointed out,

it is located at one side of, and is in parallel relation with, the runway for the car C. The air cylinder 31 extends substantially vertically and is located directly inwards of the lower end of the standard 17. It has a vertically slidable piston 36 therein and is pivotally connected at its lower end to an upstanding bracket 37. The latter is suitably attached or connected to the bed plate 16 at the upper end of the concrete pier 12. The pivotal connection at the lower end of the air cylinder 31 permits the air cylinder to swing forwards and rearwards in connection with actuation thereof. The piston 36 is provided with an upwardly extending piston rod 38 and this extends slidably through a stuffing box 39 on the central portion of the upper head of the air cylinder. Air under pressure is introduced into the upper end of the air cylinder 31 by way of a flexible conduit 40 which includes a valve (not shown). When air under pressure is introduced into the upper end of the air cylinder the piston 36 is caused to slide downwards in the cylinder and operates through the medium of the piston rod 38, the inverted T-shaped lever 32, the link 33 and the arm 34 to swing the boom into its working position. The lever 32 overlies the air cylinder 31 and consists of an upwardly extending piece 41 and a crosspiece 42 at the lower end of the piece 41. A horizontal pivot pin 43 serves to support the lever 32 so that it is free to swing or rock rearwards or forwards in a vertical plane in parallel relation with the car runway. As best shown in Figures 6 and 7 the pivot pin 43 is connected to, and projects inwards from, the central portion of the standard 17 and extends through a hole in the central portion of the crosspiece 42 of the lever 32. The upper end of the piston rod 38 is pivotally connected to the forwardly extending end of the lever crosspiece 42 by way of a clevis 44. The link 33 extends horizontally and projects in a rearward direction. The front end of such link is pivotally connected to the upper end of the upwardly extending piece 41 of the inverted T-shaped lever 32 by a horizontal pivot pin 45 in order that the link is free to swing vertically relatively to the lever. The arm 34 extends horizontally and is fixedly connected to, and projects radially from, the central portion of the mast 18. The rear end of the link 33 is connected to the outer or distal end of the arm 34 by a universal coupling 46. When the air cylinder 31 is energized by the introduction of air under pressure into its upper end the piston 36, as previously pointed out, is caused to slide downwards and operates through the medium of the piston rod 38 to rock the inverted T-shaped lever 32 in a counterclockwise direction as viewed in Figure 6. Such rocking on the part of the lever operates through the medium of the link 33 and the arm 34 to turn the mast 18 in such direction that it causes the boom 19 to swing into its working position. The counterweight 35 is suspended from the rearwardly extending end of the crosspiece 42 of the lever 32 by way of a vertically extending rod 47. The lower end of the rod is suitably fixedly connected to the counterweight and the upper end of the rod is pivotally connected to the rearwardly extending end of the crosspiece 42 by way of a clevis 48. When the air cylinder 31 is de-energized or rendered ineffective the counterweight 35 causes the inverted T-shaped lever 32 to swing or rock in a clockwise direction as viewed in Figure 6. Such rocking on the part of the lever operates through the medium of the link 33 and the

arm 34 so to turn the mast 18 as to cause the boom 19 to swing laterally into its nonworking position. The air cylinder 31 is sufficiently powerful to overcome the weight of the counterweight 35 when it is energized or rendered operative by the supply of air under pressure to its upper end. The central portion of the rod 47 extends slidably through a horizontal slot 49 in a laterally and inwardly extending bracket 50 on the standard 17 of the supporting structure. Nuts 51 and an overlying spiral compression spring 52 on the lower end of the rod 47 coact with the bracket 50 to limit and cushion counterclockwise rocking of the lever 32 in connection with actuation of the air cylinder to cause the boom 19 to swing into its working position; and nuts 53 and an underlying spiral compression spring 54 coact with the bracket 50 to limit and cushion clockwise rocking movement of the lever 32 as caused by the counterweight 35 when the air cylinder is de-energized. By adjusting the position of the nuts 51 and 53 the arc of swing of the boom 19 between its working and non-working position may be controlled.

The frame 14 carries the brush 15 as herein-after described, and is located beneath, and pivotally suspended from, the boom 19 of the supporting structure 13. It is substantially rectangular so far as contour or configuration is concerned and consists of a pair of spaced apart parallel side members 55 and a pair of spaced apart parallel cross members 56. The side members 55 extend transversely of the boom 19 and have the rear ends thereof bent downwards to form normally downwardly extending extensions 57. One of the cross members 56 extends between, and is welded or otherwise fixedly secured to, the rear ends of the side members 55 and the other cross member extends between and is fixedly secured to the central portions of the side members. The frame 14 is of rigid or unitary construction and is pivotally suspended from the boom 19 by way of a tubular cross member 58. The latter is disposed slightly forward of, and in parallel relation with, the inner cross member 56 and is spaced above, and is connected to, the side members 55 by way of a pair of brackets 59. These brackets are welded or otherwise fixedly secured to, and extend upwards from, the central portions of the side members 55 of the frame 14 and have the upper ends thereof fixedly connected to the ends of the tubular cross member 58. Said tubular cross member underlies and is in parallel relation with the boom 19 and is provided at its ends with fixed outwardly extending pintles 60. The latter are journalled in depending brackets 61 on the web of the boom 19 and permit the frame 14 to tilt or rock up and down relatively to the boom. Between and connected to the front ends of the side members 55 of the frame 14 is a counterweight 62. The latter is of such weight that it causes the frame to swing or tilt in a clockwise direction as viewed in Figures 2 and 5. In other words, the counterweight 62 urges the front ends of the frame side members 55 to swing downwards and the rear ends of such members to swing upwards.

The brush 15 of the apparatus consists of side by side circular bristle equipped sections and these are mounted on the central portion of a shaft 63. The latter is disposed in parallel relation with the cross members 56 of the frame 14 and has its ends journalled in depending bearings 64 on the lower ends of the extensions 57 in order that the brush is supported rotatably.

Rotation of the brush is effected by a unidirectional electric motor 65 and a pulley and belt connection 66. The motor 65 is mounted on a plate 67 and is arranged so that the armature shaft thereof is in parallel relation with the brush shaft 63. The plate 67 extends between and is suitably connected to certain ends of the frame cross members 53. The pulley and belt connection 66 consists of a pulley 68 on the outer end of the armature shaft of the electric motor 65, a pulley 69 on one end of the brush shaft 63, and belts 70 around the two pulleys. When the apparatus is in operation the frame 14 is swung or tilted in a counterclockwise direction as viewed in Figures 2 and 5 in order to cause the brush 15 to engage the roof of the railway car being washed. It is contemplated that in connection with a roof washing operation the brush 15 will be continuously and constantly driven in such direction that the lower portions thereof travel in the same direction as the car being washed. Water or a washing liquid is sprayed downwards onto the brush 15 by way of a spray pipe 71. The latter extends along and is suitably connected to the rearmost cross member 56 of the frame 14.

In addition to the parts or elements heretofore specifically recited the washing apparatus comprises pneumatic means 72 for tilting the rear or brush carrying end of the frame 14 downwards into its operative position against the weight of the counterweight 62, and also a power operated screw device 73.

The pneumatic means 72 is mounted for the most part on the boom 19 and comprises an air cylinder 74 and an operating connection between the air cylinder and the frame 14. The air cylinder 74 overlies the central portion of, and is disposed in substantially parallel relation with, the boom 19 and has a piston 75 slidably mounted therein. The outer end of the air cylinder is pivotally connected to a vertically extending plate 76 by a pivot pin 77 in order that the cylinder as a whole is permitted to swing upwards and downwards relatively to the boom 19. Air under pressure is admitted into the outer end of the air cylinder 74 by way of a flexible conduit 78 which includes a valve (not shown) for air controlling purposes. When the valve is opened air under pressure flows into the outer end of the air cylinder 74 and causes the piston 75 to slide towards the inner end of the air cylinder. The piston 75 is provided with an inwardly extending piston rod 79 which extends through the inner end of the air cylinder. The operating connection between the air cylinder 74 and the frame 14 consists of an arm 80, an arm 81, a link 82 and an arm 83. The arm 80 is located directly inwards of the air cylinder and extends upwards and outwards. The lower end of the arm 80 is keyed or otherwise fixedly connected to a horizontal rock shaft 84 which extends transversely of the boom and is journaled in upstanding bearings 85 on the web of the boom. The exposed end of the piston rod 79 is pivotally connected to the upper central portion of the arm 83 by a clevis 86. The arm 81 extends at substantially right angles to the arm 80 and is inclined upwards and inwards. The lower end of the arm 81 is keyed or otherwise fixedly secured to the rock shaft 84, as best shown in Figure 8. The link 82 of the operating connection between the air cylinder 74 and the frame 14 depends from the outer or distal end of the arm 81 and is located at one side of the inner end of the boom 19. The upper end of the link 82 is connected to the distal end of the arm 81 by

way of a universal coupling 87. The arm 83 is keyed or otherwise fixedly secured to the innermost pintle 60 on the tubular cross member 58 and has its outer end connected to the lower end of the link 82 by a universal coupling 88. When the air cylinder 74 is energized by the supply of air under pressure to its outer end the piston 75 slides toward the inner end of the cylinder as previously pointed out, and operates through the medium of the piston rod 79, the arms 80 and 81, the link 82 and the arm 83 to swing the rear end of the frame 14 downwards into its operative position wherein the rotary brush 15 is in contact or engagement with the roof portion of the car being washed by the apparatus. When the air cylinder 74 is de-energized by stoppage of air under pressure thereto the rear end of the brush carrying frame 14 is swung upwards into its inoperative position by the action of the counterweight 62. When the rear end of the frame 14 is in its operative position as a result of the air cylinder 74 being energized such cylinder operates yieldingly to hold the brush 15 in engagement with the roof of the car being washed. A substantially horizontal restraining rod 89 serves, in conjunction with the vertically extending plate 76, to determine or limit the arc through which the brush carrying frame 14 swings in connection with actuation or operation of the air cylinder 74 and the counterweight 62. This rod overlies, and is disposed in substantially parallel relation with, the air cylinder 74 and has at its inner end a clevis 90 whereby it is pivotally connected to the upper end of the arm 80 of the operating connection between the air cylinder and the frame 14. The central portion of the restraining rod extends slidably through an enlarged hole in the upper end of the plate 76. Nuts 91 and a spiral compression spring 92 on the outer end of the rod 89 coact with the plate 76 to limit and cushion downward swinging of the rear end of the frame 14 in response to actuation of the air cylinder 74, and nuts 93 and a spiral compression spring 94 coact with the plate 76 to limit and cushion upward swinging of the rear end of the frame in response to action of the counterweight 62. By adjusting the nuts 91 and 93 on the restraining rod 89 the size of the arc of swing or tilt of the frame 14 may be controlled.

The power operated screw device 73 is mounted on the boom 19 outwards of the pneumatic frame swinging means 72, serves as a movable mount for the air cylinder 74 and the restraining rod 89 and is adapted, as hereinafter described more in detail, either to vary the position of the arc of swing of the brush carrying frame or to increase such arc. As its parts the unit 73 comprises a cylinder 95, an elongated nut 96, a screw shaft 97, an electric motor 98 and a speed reducer 99. The cylinder 95 is disposed above and in parallel relation with the boom 19 and is fixedly connected to the latter by a pair of upstanding brackets 100. The latter have their lower ends suitably connected to the central portion of the boom 19 and their upper ends welded or otherwise fixedly secured to the ends of the cylinder. As best shown in Figure 8 of the drawings, the cylinder 95 is located adjacent the central portion of the vertically extending plate 76 and has the end thereof that is nearer such plate open. The other or outer end of the cylinder 95 embodies a head 101. The nut 96 is mounted to slide back and forth within the cylinder. The inner end of the nut extends through the open inner end of the cylinder and is fixedly connected to the central por-

tion of the vertically extending plate 76 by a bolt equipped attaching plate 102. The outer end of the nut 96 is confined within the cylinder and has an internal screw thread 103. The screw shaft 97 extends through the nut and is in screw threaded relation with the internal screw thread 103. The outer end of the screw shaft projects beyond the head 101 at the outer end of the cylinder and is mounted in the head so that it is capable of rotating without axial displacement. When the screw shaft 97 is rotated in one direction it serves to feed the nut towards the mast 18 and causes, through the medium of the vertically extending plate 76, the air cylinder 74 and the restraining rod 89 to move bodily inwards, thus either changing the position of the arc of swing of the frame as defined by the air cylinder or increasing such arc, provided, of course, that the air cylinder is energized at the same time that the nut is fed in the direction of the mast by the screw shaft. When the screw shaft is reversely rotated the nut 96 is fed in the direction of the outer end of the boom and operates, through the medium of the vertically extending plate 76, to raise the arc of swing of the frame as defined or caused by the air cylinder and the restraining rod. The electric motor 98 and the speed reducing unit 99 serve to rotate the screw shaft 97 in order bodily to adjust the position of the air cylinder 74 and the restraining rod 89. The motor 98 is of the reversible type and is mounted on one end of a transversely extending bracket 104 on the outer end of the boom 19. It is arranged so that the armature shaft thereof extends horizontally and at right angles to the boom. The speed reducer 99 is of the worm and worm gear variety. It is mounted on the other end of the bracket 104, as shown in Figure 9, and embodies a drive shaft 105 and a driven shaft 106 at right angles to the drive shaft. The drive shaft is aligned with the armature shaft of the electric motor 98 and is connected thereto by a coupling 107. The driven shaft 106 is in coaxial relation with the screw shaft 96 and is connected to the outer end of the latter by a coupling 108. When the electric motor 98 is driven in one direction the screw shaft 96 is driven in one direction and when the motor 98 is driven in the opposite direction the screw shaft is reversely driven.

When it is desired to use the apparatus to wash the roof of the railway car C the boom, prior to propulsion of the car past the apparatus, is swung into its working position wherein it overlies and extends transversely of the runway for the car. This is accomplished by energizing the air cylinder 31 by introducing air under pressure into its upper end. As heretofore pointed out, introduction of air under pressure into the upper end of the cylinder causes downward sliding movement of the piston 36 and this, in turn, effects, through the medium of the piston rod 38, the inverted T-shaped lever 32, the link 33 and the arm 34, turning of the mast 18 in such direction as to cause the boom to swing into its operative position. As soon as the front end of the car C, in connection with propulsion of the latter, approaches the apparatus the operator starts the electric motor 65 for driving the brush 15 and also energizes the air cylinder 74 so that the latter, as hereinbefore pointed out, swings the rear end of the frame downwards into its operative position wherein the brush contacts the roof of the car. As the car is propelled slowly under the frame the brush, in connection with drive or rotation thereof, effects the desired washing of

the roof of the car. In the event that the roof of the car to be washed is so low that the brush does not contact it when the frame is swung downwards into its operative position by actuation of the air cylinder 74, the screw type device 73 is operated so as to shift bodily the air cylinder 74 and the restraining rod 89 a sufficient distance towards the mast 18 to lower to the desired extent the down position of the brush. As soon as the unit 73 causes the brush to engage the roof of the car with the desired downward pressure it is stopped. In the event that the roof of the car to be washed is high the unit 73 is reversely operated so as bodily to shift towards the outer end of the boom the air cylinder 74 and the restraining rod 89. If in connection with washing of the roof of a car a protuberance, such as a hatch or ventilator, is about to be contacted by the brush the operator of the apparatus de-energizes the air cylinder 74 to the end that the counterweight 32 swings the rear end of the frame upwards into its inoperative position so that the brush will clear the protuberance. After the protuberance passes the brush the brush is lowered by again energizing the air cylinder. At the conclusion of a car washing operation the boom is swung into its nonworking position by de-energizing the air cylinder 31. As soon as such cylinder is de-energized the counterweight 35 operates to turn the mast 18 so as to swing the boom into its non-working position. It is contemplated that before the air cylinder 31 is de-energized for purposes of causing the boom to swing into its nonworking position the operator of the apparatus will actuate the screw type unit 73 so as to shift the air cylinder 74 and the restraining rod 89 to its fullest extent toward the mast 18. This causes the brush carrying frame 16 to assume a substantially vertical position and hence when the boom is in its nonworking position wherein it is located at one side of, and in parallel relation with, the runway, the frame assumes the position shown in Figure 3 and neither it nor the boom offers any obstruction to the passage of cars along the runway adjacent which the apparatus is located.

The herein described washing apparatus effectively and efficiently fulfills its intended purpose and, due to its design and construction, may be manufactured and operated economically. It involves a fundamentally new arrangement of parts so far as previously designed car washing apparatuses are concerned and is characterized by the fact that the screw type unit 73 makes it possible readily to vary the position of the arc through which the brush carrying frame swings back and forth between its operative and inoperative positions.

The washing apparatus is further characterized by the fact that the boom is so mounted that when it is in its nonworking position at one side of the runway it extends in the direction of propulsion of the car past the apparatus. Because of this and the fact that the air cylinder 31 serves when energized yieldingly to hold the boom in its working position the boom, if it, the brush or the frame is struck by a protuberance on the car being washed, will swing in the direction of its non-working position out of engagement with the protuberance. It is contemplated, however, that normally if any small sized protuberance is encountered by the brush the brush and its frame will swing upwards due to the yielding action of the air cylinder 74.

Whereas the apparatus has been specifically described in connection with the washing of the

11

roof portion of a railway car it is understood that it may be used to wash the roofs of other vehicles. It is also to be understood that the invention is not to be restricted to the details set forth since these may be modified within the scope of the appended claims without departing from the spirit and scope of the invention.

Having thus described the invention what I claim as new and desire to secure by Letters Patent is:

1. An apparatus adapted for use in connection with washing of a portion of the roof of a vehicle as the latter is propelled on a runway past it and comprising an upstanding supporting structure located at one side of the runway and embodying a substantially horizontal boom type element disposed at a higher elevation than the roof of the vehicle when the latter is on the runway and adjacent the supporting structure and mounted to swing about a vertical axis back and forth between a working position wherein it overlies, and extends transversely of, the runway and a nonworking position wherein it is disposed at said one side of, and is in substantially parallel relation with, said runway, mechanism for swinging the element back and forth between said positions, a frame carried by the element so that said frame is capable of swinging upwards and downwards about an axis in substantially parallel relation with said element, and an elongated rotary power driven brush mounted on the frame so that it is disposed in substantially parallel relation with the element and adapted when the element is in its working position and the frame is swung downwards and during propulsion of the vehicle past said supporting structure to engage the roof portion of the vehicle.

2. An apparatus adapted for use in connection with washing of a portion of the roof of a vehicle as the latter is propelled in one direction on a runway past it and comprising an upstanding supporting structure located at one side of the runway and embodying a substantially horizontal boom type element disposed at a higher elevation than the roof of the vehicle when the latter is on the runway and adjacent the supporting structure and mounted to swing about a vertical axis back and forth between a working position wherein it overlies, and extends transversely of, the runway and a nonworking position wherein it is disposed at said one side of the runway and extends in the direction of travel of the vehicle, controllable pneumatic means for swinging the element into its working position and yieldingly holding said element in said position, a frame carried by the element so that said frame is capable of swinging upwards and downwards relatively thereto, and an elongated rotary power driven brush mounted on the frame and adapted when the element is in its working position and the frame is swung downwards and during propulsion of the vehicle past said supporting structure to engage the roof portion of the vehicle.

3. An apparatus adapted for use in connection with washing of a portion of the roof of a vehicle as the latter is propelled in one direction on a runway past it and comprising an upstanding supporting structure located at one side of the runway and embodying a substantially horizontal boom type element disposed at a higher elevation than the roof of the vehicle when the latter is on the runway and adjacent the supporting structure and mounted to swing about a vertical axis back and forth between a working

12

position wherein it overlies, and extends transversely of, the runway and a nonworking position wherein it is disposed at said one side of the runway and extends in the direction of travel of the vehicle, controllable pneumatic means for swinging the element into its working position and yieldingly holding said element in such position, means independent of, and of less force than, the pneumatic means for constantly urging the element into its nonworking position with sufficient force to cause the element automatically to swing into such position when said pneumatic means is ineffective, a frame carried by the element so that said frame is capable of swinging upwards and downwards relatively thereto, and an elongated rotary power driven brush mounted on the frame and adapted when the element is in its working position and the frame is swung downwards and during propulsion of the vehicle past said supporting structure to engage the roof portion of the vehicle.

4. An apparatus adapted for use in connection with washing of a portion of the roof of a vehicle as the latter is propelled in one direction on a runway past it and comprising an upstanding supporting structure located at one side of the runway and embodying a substantially horizontal boom type element disposed at a higher elevation than the roof of the vehicle when the latter is on the runway and adjacent the supporting structure and mounted to swing about a vertical axis back and forth between a working position wherein it overlies, and extends transversely of, the runway and a nonworking position wherein it is disposed at said one side of the runway and extends in the direction of travel of the vehicle, controllable pneumatic means for swinging the element into its working position and yieldingly holding said element in such position, gravity actuated means of less force than the pneumatic means arranged and connected so that it serves constantly to urge the element into its nonworking position and adapted when the pneumatic means is rendered inoperative or ineffective to swing said element into its last mentioned position, a frame carried by the element so that said frame is capable of swinging upwards and downwards about an axis in substantially parallel relation with said element, and an elongated rotary power driven brush mounted on the frame so that it is disposed in substantially parallel relation with the element and adapted when the element is in its working position and the frame is swung downwards and during propulsion of the vehicle past said supporting structure to engage the roof portion of the vehicle.

5. An apparatus adapted for use in connection with washing of a portion of the roof of a vehicle as the latter is propelled on a runway past it and comprising an upstanding supporting structure located at one side of the runway and embodying a mast projecting an appreciable distance above the vehicle and mounted to turn about a vertical axis, and a substantially horizontal boom disposed at a higher elevation than the roof of the vehicle when the latter is on the runway and adjacent the supporting structure, having one end thereof connected to the mast at a point beneath the latter's upper end and its other end connected to said upper end of the mast by a diagonal brace, and adapted in response to back and forth turning of the mast to swing into and out of a working position wherein it overlies, and extends transversely of, the runway, mecha-

nism applied to the mast and operative to turn the latter so as to swing the boom into and out of its said working position, a frame carried by the boom so that said frame is capable of swinging upwards and downwards relatively thereto, and an elongated rotary power driven brush mounted on the frame and adapted when the boom is in its working position and the frame is swung downwards and during propulsion of the vehicle past the supporting structure to engage the roof portion of the vehicle.

6. An apparatus adapted for use in connection with washing of a portion of the roof of a vehicle as the latter is propelled on a runway past it and comprising an upstanding supporting structure located at one side of the runway and embodying a mast projecting an appreciable distance above the vehicle and mounted to turn about a vertical axis, and a substantially horizontal boom disposed at a higher elevation than the roof of the vehicle when the latter is on the runway and adjacent the supporting structure, having one end thereof so pivotally connected to the mast beneath the upper end of the latter that it swings laterally with the mast during turning of the latter while at the same time it is capable of being adjusted upwards and downwards relatively to the mast, and adapted in response to back and forth turning of the mast to swing into and out of a working position wherein it overlies, and extends transversely of, the runway, and a longitudinally extensible diagonally positioned brace extending between, and pivotally connected to, the other or distal end of the boom and the upper end of the mast, mechanism means applied to the mast and operative to turn the latter so as to swing the boom into and out of its said working position, a frame carried by the boom so that said frame is capable of swinging upwards and downwards relatively thereto, and an elongated rotary power driven brush mounted on the frame and adapted when the boom is in its working position and the frame is swung downwards and during propulsion of the vehicle past the supporting structure to engage the roof portion of the vehicle.

7. An apparatus adapted for use in connection with washing of a portion of the roof of a vehicle as the latter is propelled on a runway past it and comprising an upstanding supporting structure located at one side of the runway, embodying a substantially horizontal boom type element disposed at a higher elevation than the roof of the vehicle when the latter is on the runway and adjacent the supporting structure, and mounted to swing laterally back and forth between a working position wherein it overlies, and extends transversely of, the runway and a nonworking position wherein it is disposed at one side of said runway, a substantially rectangular frame having the intermediate portion thereof pivotally suspended from the element so that said frame is capable of tilting up and down about an axis in substantially parallel relation with the element, and arranged so that when the element is in its working position it extends lengthwise of the runway, an elongated rotary motor driven brush supported by, and extending across, one end of the frame and adapted when the element is in its working position and the one frame end is tilted downwards and during propulsion of the vehicle past the supporting structure to engage the roof portion of the vehicle, pneumatic means extending between the element and the frame and operative when energized to tilt the frame in

one direction, and means for limiting tilting movement of the frame relatively to said element.

8. An apparatus adapted for use in connection with washing of a portion of the roof of a vehicle as the latter is propelled on a runway past it and comprising an upstanding supporting structure located at one side of the runway, embodying a substantially horizontal boom type element disposed at a higher elevation than the roof of the vehicle when the latter is on the runway and adjacent the supporting structure, and mounted so that it is capable of moving back and forth between a working position wherein it overlies, and extends transversely of, the runway and a nonworking position wherein it is disposed away from said runway, a substantially rectangular frame having the intermediate portion thereof pivotally suspended from the element so that said frame is capable of tilting up and down about an axis in substantially parallel relation with said element, and arranged so that when the element is in its working position it extends lengthwise of the runway, an elongated rotary motor driven brush supported by, and extending across, one end of the frame and adapted when the element is in its working position and the one frame end is tilted downwards and during propulsion of the vehicle past the supporting structure to engage the roof portion of the vehicle, pneumatic means mounted on the element, operatively connected to the frame, and arranged and adapted when energized to tilt said one end of the frame downwards, a counterweight mounted on the other end of the frame and operative when said pneumatic means is ineffective to cause said one end of the frame to tilt upwards, and means for limiting tilting movement of the frame relatively to said element.

9. An apparatus adapted for use in connection with washing of a portion of a roof of a vehicle as the latter is propelled on a runway past it and comprising an upstanding supporting structure located at one side of the runway, embodying a substantially horizontal boom type element disposed at a higher elevation than the roof of the vehicle when the latter is on the runway and adjacent the supporting structure, and mounted to swing laterally back and forth between a working position wherein it overlies, and extends transversely of, the runway and a nonworking position wherein it is disposed at one side of, and in substantially parallel relation with, said runway, pneumatically actuated mechanism for swinging the element into its working position, counterweight means for automatically swinging said element into its non-working position when the mechanism is de-energized, a substantially rectangular frame having the intermediate portion thereof pivotally suspended from the element so that said frame is capable of tilting up and down, and arranged so that when the element is in its working position it extends lengthwise of the runway, an elongated rotary motor driven brush supported by, and extending across, one end of the frame and adapted when the element is in its working position and the one frame end is tilted downwards and during propulsion of the vehicle past the supporting structure to engage the roof portion of the vehicle, pneumatic means mounted on the element, operatively connected to the frame and, arranged and adapted when energized to tilt said one end of the frame downwards, a counterweight

mounted on the other end of the frame and operative when said pneumatic means is ineffective to cause said one end of the frame to tilt upwards, and means for limiting tilting movement of the frame relatively to said element.

10. An apparatus adapted for use in connection with washing of a portion of a vehicle as the latter is propelled on a runway past it and comprising a supporting structure adjacent the runway, a frame provided with a rotary power driven brush and mounted on the supporting structure so that said frame is movable towards and away from the vehicle, an air cylinder having a predetermined stroke, operatively connected to the frame and adapted when energized after movement of the frame away from the vehicle to move the frame towards the vehicle, and a power operated combined mounting and adjusting unit for the air cylinder arranged and adapted when operated to shift the air cylinder bodily in order either to change the position of its stroke or augment the latter.

11. An apparatus adapted for use in connection with washing of a portion of a vehicle as the latter is propelled on a runway past it and comprising a supporting structure adjacent the runway, a frame mounted on the supporting structure so that said frame is capable of swinging toward and away from the vehicle and provided at its distal end with a rotary power driven vehicle washing brush, an air cylinder having a predetermined stroke, operatively connected to the frame and adapted when energized after the frame has been swung away from the vehicle to swing the frame towards the vehicle, and a power operated combined mounting and adjusting unit for the air cylinder extending between, and connected to, said cylinder and supporting structure and arranged and adapted when operated to shift the air cylinder axially in order 40

either to change the position of its stroke or augment the latter.

12. An apparatus adapted for use in connection with washing of a portion of a vehicle as the latter is propelled on a runway past it and comprising a supporting structure adjacent the runway, a frame provided with a rotary power driven brush and mounted on the structure so that said frame is movable towards and away from the vehicle, an air cylinder having a predetermined stroke, operatively connected to the frame and adapted when energized after movement of the frame away from the vehicle to move the frame toward the vehicle, and a power operated combined mounting and adjusting unit for the air cylinder arranged and adapted when operated to shift the air cylinder axially in order either to change the position of its stroke or augment the latter, and embodying a screw shaft mounted on the supporting structure so that it is rotatable without axial displacement and provided with power means for driving it in either direction, and a nut mounted on the screw shaft and connected fixedly to said air cylinder.
